GEORGE H. MALLORY, OF PIERCE, NEBRASKA.

HAY-RACK.

1,280,513.

Specification of Letters Patent. Patented Oct. 1, 1918.

Application filed March 13, 1918. Serial No. 222,147.

To all whom it may concern:

Be it known that I, GEORGE H. MALLORY, a citizen of the United States, residing at Pierce, in the county of Pierce and State 5 of Nebraska, have invented certain new and useful Improvements in Hay-Racks, of which the following is a specification.

This invention relates to wagons, and more especially to hay racks adapted to be 10 mounted on the running gear of an ordinary wagon in place of the bed or body thereof; and the object of the same is to provide such a hay rack with standards which may be used as legs or feet when the rack is removed 15 from the running gear.

Other objects will appear in the following specification, and reference is made to the drawings, wherein:—

Figure 1 is a side elevation of this hay 20 rack with its standards raised to their limit,

Fig. 2 is a plan view of this hay rack,

Fig. 3 is an end elevation with its standards run down and serving as feet.

Two parallel sills 1 stand on edge and are 25 bridged by cleats 2, and these sills may rest on the bolster B inside the stakes S as seen at the left in Fig. 1 where the bolster is outside the cleat, or at the right of Fig. 1 where the bolster is inside of the cleat, the disposition 30 depending on the length of the running gear and therefore the spacing of its bolsters. Secured across and extending beyond the sills are end bars 3 and intermediate cross bars 4, upon and over which a flooring 35 may be laid if it is desired, although the same is not shown in the drawings. The end bars carry upright posts 5 connected by transverse slats 6 forming the ends of the rack; and the intermediate cross bars carry 40 uprights 7 at their ends, while the sides of the rack are formed by oblique strips 8 secured to the posts and uprights as perhaps best seen in Fig. 1. Thereby is produced an extremely light hay rack which when 45 emptied can be lifted onto or off of the running gear by two men very easily, if it be made in the proper proportions and of the proper materials.

The principal feature of my invention is 50 to provide improved standards at the ends of this rack, made up of elements which can be employed as legs or feet to hold the rack upright when it is put on the ground or barn floor. The numeral 10 designates 55 guides of strap metal, each substantially of U-shape with feet at its ends, and these are

nailed or screwed to the slats 6 and the end bars 3 as seen in Fig. 3 at the left, the disposition of each two guides being such that together they constitute an oblique channel 60 for one of the bars of the standard. The two standard bars are indicated by the numeral 12, and each is slidably mounted through a pair of said guides, the bar being provided near its lower end with a transverse perforation 13 and a little higher with a transverse perforation 14. A pin 15 is now passed horizontally through the lowermost guide, the same being provided with holes for that purpose, and through one of 70 the perforations 13 or 14 in the bar 12. When these standard bars are run up as indicated in Fig. 1 they serve the ordinary function of standards at the extremities of the hay rack, and an overhead longitudinal 75 pole may connect them as usual but as is not thought necessary to show in the drawings. At this time their lower ends will be about flush with the lowermost guides, and the pins 15 will be run through the lower 80 perforations 13. When now the rack is to be removed from the running gear, the pins 15 are withdrawn and the standard bars 12 allowed to drop to the position best seen in Fig. 3, and the pins 15 reinserted through the holes in the lower guide or guides and the perforations 14 in the bars. The latter are therefore no longer projected above the 85 ends of the rack but their lower ends project downward alongside the sills and constitute legs, their lower extremities being feet standing about parallel with the lower edges of the sills and therefore resting on the ground or barn floor when the rack is removed from the vehicle. It is obvious that 90 a greater adjustment could be given these bars if they were provided with additional perforations. It is of course quite possible to insert the pins 15 through the guides 10 in a direction at right angles to that shown, 100 so that one end of the pins will stand within the slats; and while I have spoken of pins, it is of course quite possible to use other fastening means such as bolts or the like. I 95 therefore retain the broadest latitude in this 105 respect. These standard bars are shown as converging to an extent which would make their upper ends meet when their lower ends are about flush with the end cross bars 3, but this convergence is not absolutely necessary as the parts might be set to require the 110 standards to run higher before the pins

were inserted in the lowermost perforation 13. Also, while I have shown but a single perforation 14 to hold the standard bar when run down through the guides, it is 5 obvious that there might be several of these perforations so that the feet at the lower end of the bars could be set flush with the lower edges of the sills, or even below them to take the entire weight of the rack off the 10 sills if preferred. The proportions and materials of parts will be left to the manufacturer.

What is claimed as new is:—

1. In a hay rack, the combination with the 15 sills, the sides, and the ends; of guides carried by each end and disposed in two lines converging upward, certain of said guides having transverse holes, standard bars slidably mounted through said guides and each 20 having a plurality of perforations, and pins

removably engaging said holes and selectively engaging said perforations, for the purpose set forth.

2. In a hay rack, the combination with the 25 body structure including slatted ends; of a standard for each end made up of two bars converging upward and each provided with a series of transverse perforations, guides secured to the slats of the end on lines converging upward toward each other and certain of said guides having transverse holes, 30 and pins engaging the holes and selectively engaging the perforations, for the purpose set forth.

In testimony whereof I affix my signature 35 in presence of two witnesses.

GEORGE H. MALLORY.
